[57] CLAIM

The ornamental design for a golf putter, as shown and described.

DESCRIPTION

FIG. 1 is a perspective view of a golf putter taken from above and looking toward the back and one side showing my new design;

FIG. 2 is an enlarged perspective view similar to FIG. 1;

FIG. 3 is a perspective view similar to FIG. 2 but looking toward the front and the opposite side thereof;

FIG. 4 is a bottom view thereof;

FIG. 5 is a side view thereof; and,

FIG. 6 is a rear elevational view thereof.

FIGS. 2, 3, 5 and 6 are shown broken away to indicate indeterminate length.
